IMPULSE-CONTROLLED TIMER FOR ENERGIZING DEVICES FOR PRESELECTED PERIODS

Melvin E. Nelson, Burbank, Calif., assignor to
Mel M. Burns

Application December 20, 1946, Serial No. 717,454

5 Claims. (Cl. 185—40)

This invention relates to timing devices for measuring time, and particularly to devices that measure time in terms of a predetermined unit or a multiple thereof. It has particular utility in connection with coin-controlled mechanisms for controlling the time of operation in accordance with the number of coins inserted.

An object of the invention is to provide an impulse-controlled mechanism for measuring time in predetermined increments, which mechanism is inexpensive to manufacture and reliable in operation and which responds to impulses of small energy.

A more specific object is to provide an impulse-controlled timing mechanism in which: (1) the energy of a spring is used to shift an actuating element in response to a controlling pulse; (2) the actuating element is returned to its initial position at a constant speed by a clock motor; and (3) the spring is automatically rewound by the return of the actuating element.

Other more specific objects and features of the invention will become apparent from the description to follow.

Essentially, the invention comprises a switch-actuating element movable in one direction by a spring mechanism under the control of an escapement in response to controlling impulses, with a timing motor for restoring the switch-actuating element to its initial position at a constant speed, in which the restoring movement of the motor also reloads the spring, so that the latter is always effective to act in response to a received impulse.

In the drawing:

Fig. 1 is a front elevation view of one embodiment of the invention.

Fig. 2 is a detail vertical section taken along the line II—II of Fig. 1; and

Fig. 3 is a circuit diagram of the electrical system of the mechanism.

Referring first to Fig. 1, the apparatus there shown comprises a differential mechanism consisting of a pair of worms 10 and 11 respectively, both of which mesh with a common worm wheel 12. As is clearly apparent from the drawing, the worms 10 and 11 are parallel to each other and engage the worm wheel 12 at diametrically opposite points. Furthermore the worm wheel 12 is supported for free rotation on a stub shaft 13 which is slidably mounted for free vertical movement. Thus referring to Fig. 2, the shaft 13 extends through a slot 14 in a frame plate 15 on which the mechanism is mounted. The shaft is supported against tilting movement by a washer

16 which is positioned between the worm wheel 12 and the front face of the plate 15, and a nut 17 which is threaded onto the rear end of the shaft 13 and which slides along the rear face of the plate 15. The worm wheel 12 may be retained on the shaft 13 against the washer 16 by a washer 18 and a split retaining ring 19 which is mounted in an annular groove provided therefor on the shaft 13.

10 The worms 10 and 11 may be conveniently supported in bearings constituted by ears 20 extending forwardly from the base plate 15 and having apertures therein through which reduced end portions 22 of the worms 10 and 11 project.

15 In operation, the worm wheel 12 and its supporting shaft 13 are moved downwardly by rotation of the worm 11, and upwardly by rotation of the worm 10. The arrangement is such that the worm 11 moves through one complete revolution at a time, causing the worm wheel 12 to be moved down a predetermined distance. Whenever the worm wheel 12 is moved out of its uppermost position the worm 10 is actuated in direction to restore the worm wheel to its uppermost position.

20 Movement of the worm 11 is produced by a helical spring 25 which is connected to the lower reduced section 22 of the worm and is constantly loaded to apply torque to the worm. Movement of the worm in response to the torque is produced whenever an escapement mechanism is actuated, this escapement mechanism normally restraining the worm 11 from rotation.

25 As shown in the drawing, the escapement mechanism comprises a pin 26 extending radially from the extension 22 at the upper end of worm 11, which pin is normally engaged by an arm 27 on a lever 28 which is fulcrumed at 29 to the frame plate 15. The lever 28 is normally retained in the position shown, in which the arm 27 engages the pin 26, by a tension spring 30 which is stretched between the lower end of the lever 28 and the frame plate 15. At its upper end, the lever 28 carries a pole piece 31 which is associated with an actuating magnet 32.

30 Whenever the magnet 32 is energized, the pole piece 31 is attracted thereby to rock the lever 28 counter-clockwise and disengage the arm 27 from the pin 26, whereupon the worm 11 is rotated through half a revolution by the spring 25. At the end of this half revolution the worm is stopped by engagement of the pin 26 with a second arm 33 on the lever 28. However, when the magnet 32 is deenergized, the lever 28 is restored to normal position by the spring 30, thereby carrying the arm 33 out of engagement with the pin

26 and permitting the worm 11 to move through another half revolution when it is again stopped by engagement of the pin 26 against the arm 27.

It will be observed that the escapement mechanism described functions to permit one complete revolution of the worm 11 by the spring 25 in response to each energizing impulse applied to the magnet 32, independent of the length of the impulse.

When the worm wheel 12 is in its uppermost position, the front end of the shaft 13 bears against a plunger 35 of a switch 36, which switch contains contacts that are opened when the plunger 35 is depressed and are closed when the plunger is released. Referring to Fig. 3, it will be observed that contacts 36a of this switch 36 are connected in series with a power line 37 and a motor 38, so that the motor 38 runs whenever the switch contacts 36a are closed. As shown in Fig. 3 the circuit for supplying impulses to the magnet 32 may also include this same power line 37 in conjunction with a switch 44. One field of use for the present invention is in coin controlled mechanisms, and, in Fig. 1, the switch 44 is shown as having an actuating arm 39 which is rocked to actuate the switch 44 in response to movement of a coin through a coin chute 40. However, the present invention is in no sense limited to coin actuated devices, and the switch 44 of Fig. 3 may be any desired type of switch controlled in any desired manner.

The motor 38 is preferably of the constant speed type such as a clock motor, and drives the worm 10. As shown in Fig. 1, the motor 38 has a shaft 42 which is directly connected to the upper extension 22 of the worm 10. The direction of rotation of the shaft 42 is such as to rotate the worm 10 in direction to move the worm wheel 12 upwardly and restore it to its uppermost position in which the worm shaft 13 re-engages the plunger 35 of the switch 36 and opens the switch contacts 36a to stop the motor 38.

A feature of the invention is the automatic winding of the spring 25 so that it is constantly loaded to rotate the worm 11 whenever the escapement mechanism is actuated by energization of the magnet 32.

To this end, one end of the spring 25 is connected to the worm 11 and the other end is connected to the worm 10. Obviously since the worms are parallel to each other the spring 25 must be bent into U shape in order to be connected to both the worms. It is also desirable to support the spring 25 and this may be done by the U-shaped wire support 40 which extends through the spring 25 and extends into recesses 41 provided therefor in the lower ends of the extensions 22, 22 on the worms 10 and 11 respectively.

The support 40 fits loosely within the recesses 41 so that it does not interfere with the free rotation of the worms. It is retained in position by the inherent tension of the spring 25. As clearly shown, the ends of the spring 25 may be coupled to the lower extensions 22 on the worms by extending the ends of the spring through diametrical apertures 43 provided for that purpose in the extensions 22, 22.

Of course the spring 25 must not drive the worm 10. Ordinarily this is prevented by the frictional resistance to rotation of the motor shaft 42 when the motor 38 is of the conventional clock type containing a speed-reducing gear train or transmission. If the friction of the motor is

insufficient to resist the reaction of spring 25, a ratchet mechanism can be provided to prevent reverse motion of the worm 10.

Since devices of this type are usually employed for the control of some electrically actuated device, auxiliary contacts 36b are preferably provided on the switch 36, which contacts may be connected into the electrical circuit of a device to be controlled.

10. It will be observed that a plurality of impulses can be successively applied to the magnet 32 and that each impulse will cause the worm wheel 12 to be moved downwardly a predetermined distance. In other words, the effect of a series of impulses applied to the magnet 32 is stored up by the movement of the worm wheel 12. For example, if ten impulses are applied to the magnet 32, the worm wheel 12 will be moved downwardly ten times as far as it would be moved in response to one impulse, and the motor 38 will have to run ten times as long to restore the worm wheel 12 into its uppermost position in which it opens the switch 36.

Although, for the purpose of explaining the invention, one specific embodiment thereof has been described in detail, various departures from the exact construction shown can be made without departing from the invention which is to be limited only to the extent set forth in the appended claims.

I claim:

1. A device of the type described comprising: a differential mechanism including a driven member having a normal position of rest and two separate driving members therefor, each driving member being capable of driving said driven member independently of the other member; normally wound spring means in driving relation with one of said driving members for driving the latter in direction to move said driven member away from said normal position; control means for permitting controlled movement of said one driving member by said spring means; motor means for driving said other driving member in direction to move said driven member back to its normal position; means actuated by movement of said driven member out of normal position for causing said motor means to drive said other driving member and actuated by movement of said driven member into normal position for causing said motor means to cease driving said other driving member and means coupling said spring means to said other driving member for rewinding the spring means during return movement of said driven member by said motor means.

2. A device as described in claim 1 in which said two driving members are rotary members having parallel axes and said spring means comprises a helical spring having a return bend therein whereby the ends are coaxial with respect to said driving members, and means connecting each end of said spring to its coaxially associated driving member.

3. A device as described in claim 1 in which said two driving members are rotary members having parallel axes and said spring means comprises a helical spring having a return bend therein whereby the ends are coaxial with respect to said driving members, means connecting each end of said spring to its coaxially associated driving member, and a U shaped guide rod extending through said helical spring for supporting it.

4. A device as described in claim 1 in which said driven member consists of a worm wheel and said driving members consist of a pair of parallel

worms meshing with said wheel; a shaft supporting said worm wheel for free rotation; and means supporting said shaft for linear movement through a path parallel to said arms.

5. A device for measuring predetermined increments of time comprising: a movable member having a normal position of rest; normally wound spring means for moving said member away from said normal position; control means for permitting controlled substantially instantaneous movement of said member by said spring means through predetermined increments of distance; motor means for returning said member to said normal position at a constant speed; means actuated by movement of said member out of said position of rest for causing said motor means to drive said member and actuated by movement of said member into said position of

rest for causing said motor means to cease to drive said member; and means coupling said motor means to said spring means for rewinding the latter during the return of said member to normal position.
